UNITED STATES PATENT OFFICE.

WARREN F. JOHNSTON, OF WEST CARROLLTON, OHIO.

SPARK-PLUG-INSULATING MEANS.

1,222,768.

Specification of Letters Patent. Patented Apr. 17, 1917.

Application filed April 14, 1915. Serial No. 21,232.

To all whom it may concern:

Be it known that I, WARREN F. JOHNSTON, a citizen of the United States, residing at West Carrollton, in the county of Montgomery and State of Ohio, have invented new and useful Improvements in Spark-Plug-Insulating Means, of which the following is a specification.

This invention relates to new and useful improvements in spark-plug insulating means.

The object of my invention is to provide an insulation for spark-plugs, which is cheaper, more efficient and durable than that which is now employed. Furthermore, as my improved insulation will readily take a thread, less labor and fewer parts are required to insert and clamp the same within the shell than would otherwise be necessary. Accordingly, the spark-plug may at all times be readily cleaned or repaired with little trouble and practically no attendant danger of breaking or otherwise injuring the insulation or other parts during the insertion or removal process.

The preferred forms of embodiment of my invention are illustrated in the accompanying drawings, of which Figure 1 is an elevational view of a spark-plug, partly broken away, to disclose my improved insulating means in place therein. Fig. 2 is a sectional view of the bakelite insulating member before being screwed into the shell and before the porcelain insulation and nickel electrode has been secured thereto. Fig. 3 is a sectional view of the porcelain insulating member as constructed for insertion in the bakelite and the reception of the electrode. Fig. 4 is an elevational view of the nickel electrode. And Fig. 5 is a sectional view of the bakelite, porcelain and the nickel electrode all molded together in one piece.

Throughout the specification and drawings, similar reference characters denote corresponding parts.

In a detailed description of my invention, the numeral 1 designates the common form of a metal spark-plug shell having a lower externally screw-threaded portion 2, so that it may be screwed into the cylinder of an explosive engine. The shell 1 is also provided with the usual tubular bore 3, which terminates at its upper end in an enlarged internally screw-threaded portion 4 adapted to receive a bakelite insulating member 5 to be now described.

As is well known in the insulation art, bakelite is a condensation product which results when phenol and formaldehyde are boiled in the presence of sodium hydroxide. In its solid form, it is infusible, insoluble and capable of being molded or shaped into various forms. It readily takes a thread, and while great heat tends to slightly soften it, it can not be brought into fusion.

Spark plugs as at present constructed, contain porcelain or mica as insulating material. These substances cannot be threaded, and accordingly must be held in place by numerous clamping nuts and other parts which make the operation of inserting or removing the insulation and electrodes a difficult one which frequently results in the breaking or injuring of the porcelain or mica and their connections.

It is with a view to obviating the above difficulties that I have provided the insulating member 5 which is constructed of bakelite or equivalent material. Referring to Figs. 1 and 2, the bakelite insulating member 5 is molded with a lower externally-threaded cylindrical end 6 adapted to be screwed into the enlarged screw-threaded portion 4 of the spark-plug shell 1. Formed above its screw-threaded end 6 is an annular collar or flange 7, above which is a hexagonal portion 8, said bakelite member terminating at its upper end in a dome shaped portion 9. Passing through the central portion of the bakelite member 5 is a tubular bore 10 adapted to readily receive the upper end of an electrode 11 preferably constructed of nickel.

The tubular bore 10 of the bakelite member 5 terminates at its lower end in an enlarged cylindrical mouth portion 12 adapted to receive the upper end of a cylindrical insulating member 13 constructed of porcelain or other suitable silicate. This porcelain insulating member 13 terminates at its lower end in a hollow or petticoat portion 14, from which there extends upwardly through said member, a tubular bore 15 having the same diameter as, and in a position to come flush with, the tubular bore 10 in the bakelite member 5.

Resting upon the upper surface of the shell 1, is a preferably copper asbestos washer 16 adapted to be compressed by the flange 7 when the bakelite member 5 is screwed into said shell, as shown in Fig. 1. The porcelain insulating member 13 is now forced upwardly through the shell 1, until its

upper end is firmly within the socket or enlarged cylindrical mouth portion 12 in the bakelite insulating member 5. The tubular bores 10 and 15 will now be in alinement to receive the nickel electrode 11, whose threaded end 17 is forced through and above them to receive a terminal nut 18. Provided on the electrode 11, a short distance from its lowermost end, is an annular flange 19 whose diameter is larger than that of the tubular bore 15 and smaller than that of the petticoat portion 14 of the porcelain insulating member 13. Accordingly, when the terminal nut 18 is tightened, the electrode 11 will be elevated to bring its flange portion 19 into engagement with the bottom of the porcelain member 13, to hold the upper end of the latter firmly within the socket or enlarged cylindrical mouth portion 12 of the bakelite member 5.

When the insulating and other parts have been assembled within the shell 1 as above described, the lower end of the electrode 11 will extend below said shell to a point a short distance above the bent end of a side electrode 20 suitably secured within said shell, a sufficient gap being produced between the said electrodes to insure an effective spark.

From the foregoing it will appear how readily the bakelite and porcelain insulating members may be inserted within the shell 1, and the small number of parts required to firmly hold them in place. With less ease may they be inserted or removed by employing the one-piece construction shown in Fig. 5. In this construction the porcelain insulating member 13 preferably has the form of an inverted cone, whose upper end terminates in an annular flange portion 21 which is molded in the lower threaded end 6 of the bakelite member 5. The center nickel electrode 11 is molded in both the bakelite and porcelain, and extends a sufficient distance below the latter to form with the side electrode 20 a gap sufficient to insure an effective spark. Suitably cast into the dome portion 9 of the bakelite member 5, is a hexagonal metallic piece 22 having an upwardly projecting screw-threaded rod 23 adapted to receive the terminal nut 18. The upper end of the electrode 11 extends into the metallic piece 22, which is provided for the purpose of insuring a good electrical connection between the feed wire (not shown) and the electrode.

The one-piece construction above described is readily screwed into and out of the shell 1, thus obviating entirely the necessity of employing the clamping means commonly used, and with no attendant injury to any of the parts comprised within the insulating unit.

It is apparent from the foregoing that my improved process of uniting porcelain or

other suitable silicate, to bakelite, insures insulating means for a spark-plug which may be readily inserted in, and removed from the shell of the plug. The small number of parts which this combination makes necessary, is an assurance against leakage of the current and breakage of insulating and other parts. Porcelain, which stands better than almost any other known agent, the intense heat within the cylinder, is placed in that part of the plug which is exposed to the greatest heat, while the bakelite, which takes a thread, is screwed in the upper portion of the shell and united, by molding or otherwise, to the porcelain below. In other words, these two substances to wit, bakelite and porcelain, have singly qualities which, when combined in my construction, produce a spark-plug that is cheaper to manufacture, and more efficient and durable when made, than the plugs which are commonly used.

I do not wish to be limited to the details of construction and arrangement herein shown and described, and any changes or modifications may be made therein within the scope of the subjoined claims.

Having described my invention, I claim:

1. In a spark-plug, the combination with the shell thereof, of a bakelite insulating member threaded for insertion in the upper portion of said shell, and a silicate insulating member adapted to be secured to the bottom portion of said bakelite member, substantially as described.

2. In a spark-plug, the combination with the shell thereof, of a bakelite insulating member threaded for insertion in the upper portion of said shell, a porcelain insulating member adapted to be firmly secured to the bottom portion of said bakelite member, and an electrode passing through both members, substantially as described.

3. In a spark-plug, the combination with the shell thereof, of a bakelite insulating member threaded for insertion in the upper portion of said shell, said member provided with a tubular bore terminating at its lower end in an enlarged socket portion, a porcelain insulating member whose upper end is adapted to be inserted in said socket, and containing a tubular bore in a position to come flush with the tubular bore in said bakelite member, and an electrode adapted to be passed through both of said bores, substantially as described.

4. In a spark-plug, the combination with the shell thereof, of a bakelite insulating member threaded for insertion in the upper portion of said shell, a silicate insulating member adapted to be secured to the bottom portion of said bakelite member, an electrode passing through both of said members, and means attachable to said electrode for clamping said members firmly together, substantially as described.

5. In a spark-plug, the combination with the shell thereof, of a bakelite insulating member threaded for insertion in the upper portion of said shell, said member provided with a vertical tubular bore terminating at its lower end in an enlarged socket portion, a porcelain insulating member whose upper end is adapted to enter said socket, and containing a vertical tubular bore of the same diameter as, and in a position to come flush with, the tubular bore in said bakelite member, an electrode with a threaded upper end adapted to pass through both of said bores, a terminal nut for the threaded end of said electrode above said bakelite member, and a flange on the lower end of said electrode, adapted to engage and force the porcelain member firmly against the bakelite member when said terminal nut is tightened, substantially as described. 25
- 10 6. In a spark-plug, the combination with the shell thereof, of a bakelite insulating member threaded for insertion in the upper end of said shell, said member provided with a vertical tubular bore terminating at 30
- 15 its lower end in an enlarged socket portion, a porcelain insulating member whose upper end is adapted to enter said socket, and containing a vertical tubular bore of the same diameter as, and in a position to come flush with, the tubular bore in said bakelite member, an electrode with a threaded upper end adapted to pass through both of said bores, a terminal nut for the threaded end of said electrode, said porcelain member terminating at its lower end in a petticoat portion, and a 35 flange on the lower end of said electrode, adapted to pass upwardly through said petticoat portion of said porcelain member, to engage and force the latter firmly against the bakelite member when the terminal nut 40 is tightened, substantially as described.
- 20 In testimony whereof I have hereunto set my hand this 12th day of April, 1915.

WARREN F. JOHNSTON.
